GEORGE N. FITCH, OF VENTURA, CALIFORNIA

EXPANSIBLE BIT

Application filed May 6, 1930. Serial No. 450,168.

This invention relates to an expandible bit comprising cutter carriers fulcrumed in the body so that their cutter ends may be swung outwardly to expanded position and inwardly to collapsed position and an axially movable mandrel to expand and collapse the carriers. An object of this invention is to provide an expandible bit of the character described having a mandrel which is movable or advanceable in one direction for expansion and collapse. Another object of this invention is to provide a mandrel which may be advanced hydraulically. A further object of this invention is to provide a mandrel and trigger mechanism releasable by a plummet to enable collapse of the carriers. A still further object of this invention is to provide an expandible bit of the character described having a novel type of mandrel to coact with the cutter carriers.

These objects together with other objects and corresponding accomplishments are obtained by means of the embodiment of my invention illustrated in the accompanying drawings, in which:—

Fig. 1 is an axial section showing a bit with parts in initial collapsed position; Figs. 2, 3, and 4, are sections as seen on the lines correspondingly numbered in Fig. 1; Fig. 5 is a fragmentary side view showing a cutter mounted upon a carrier; Fig. 6 is a section through the bit, the mandrel being shown in expanded position; and Fig. 7 is a view similar to Fig. 6 showing the cutters in final collapsed position.

Referring more particularly to the drawings, a slotted body 10 has a pin end 11 for attachment to a socket 12 forming a part of a drill string. The pin and socket connection is merely illustrative, as other well known means may be provided for connecting the body of the bit to the drill pipe. In the construction shown, slots 14 are provided for four cutter carriers, although the invention is not limited to any particular number of cutter carriers. On the exterior of the body are longitudinally extending recesses to accommodate circulation and these are marked 13 and best shown in Fig. 4. The recesses extend

from the head portion of the body marked 10a to the lower end. In the slots 14 are cutter carriers comprising arms 15 pivoted intermediate their ends on pins 16 extending transverse to the drilling axis of the bit. Pinned to the lower ends of the carriers are cutters 17. However, it will be apparent that any suitable type of cutter may be used, and if desired, the carriers and cutters may be made integral. The inner faces of the carriers are spaced from one another to accommodate a mandrel. The inner faces slope from the pivot axis so that sufficient clearance is provided for swinging of the cutters without interference by the mandrel. At the upper end of the carriers is a cavity 18 formed by opposing recesses. Below the pivot pin 16 is a cavity 19 formed by recesses, and the carriers are cut away to provide a third and lowest cavity as indicated by 20.

The head end of the body has a bore in which is slidably mounted a telescopic tubular sleeve 21. This sleeve has its wall slotted at diametrically opposite points and pivotally mounted therein are trigger fingers 22. The lower ends of the fingers are squared and adapted to rest upon a seating shoulder or ledge 23 as shown in Figs. 1 and 6. The upper inner ends of the fingers are bevelled as indicated by 24 to permit a "go-devil" or plummet to pass between them to the position shown in Fig. 7. An arresting shoulder 25 is provided in sleeve 21 for the "go-devil" which is marked 26 in Fig. 7. The bore of the connector sleeve is reduced in diameter at 27 to be engaged by an enlargement on the mandrel. In the wall of sleeve 21 are perforations 28 for registering with an annular groove 29 from which extend ducts 30 leading to circulation passages 31. Circulation passages 31 extend from the bore in the head at the ports 32 to the lower end of the body adjacent the cutters. The ports 32 are so situated, that when the connector sleeve is in its upper position as shown in Figs. 1 and 6, the ports are closed and when the connector sleeve is in the lower position shown in Fig. 7, the ports 32 are open to circulation passing from the drill pipe. When the connector sleeve is in its upper

position as shown in Figs. 1 and 6, the perforations 28 register with the annular groove 29 so that circulation may pass through the ducts 30 to the circulation passages 31.

- 5 The mandrel consists of a tubular member 33 with an enlargement 34 at the upper end to coact with the seat 27 in the connector and a valve seat 35 at the lower end for a ball check 36. On the mandrel is an upper head 10 37 and a lower head 38. These heads are of bull nose form tapering at their lower portion and are of such overall dimensions, as to fit within the cavities 18, 19 and 20.

The heads 37 and 38 are so spaced that, 15 when head 38 is in cavity 19, head 37 is in cavity 18 with the carriers collapsed as shown in Fig. 1, the upper head 37 clearing the carriers. When the mandrel is lowered to the position shown in Fig. 6, the head 38 is disposed between the carriers and the head 37 is disposed in the upper cavity 18 clearing the carriers. This causes expansion of the carriers. In the position shown in Fig. 7, 20 the mandrel has been still further advanced, and the head 37 is between the carriers, while the lower head 38 is clear of the carriers and rests in cavity 20. In this position, the upper head will have expanded the carriers.

The operation of the bit is as follows: initially, the connector sleeve 21 is disposed in the position shown in Fig. 1 with trigger fingers 22 disposed on the annular seat 23. Leaf springs on the fingers tend to maintain the latter in their retaining positions. It 30 is obvious, that the connector sleeve will then be held against downward movement. The mandrel 33 is then positioned with the lower head 38 in the intermediate cavity 19 and with the upper head 37 clear, the enlargement 34 being disposed so that the mandrel may have a limited downward movement. The cutter carriers are collapsed, and the bit may be inserted in the well. When the bit has 40 reached the position at which it is desired to drill, circulation is started down through the drill string. Prior to the starting of circulation, any liquid which is in the well hole may have passed upwardly by the check valve 36. As circulation is inaugurated, the check 45 valve 36 is closed and the hydraulic pressure will cause the mandrel to be advanced to the position shown in Fig. 6. In this position the cutters are expanded. The delivery of circulation fluid to the cutters is provided for by 50 the perforations 28, annular recess 29, branch ducts 30 and circulation passages 31. The bit may now be turned to drill. When it is desired to pull the bit from the hole, a "go-devil" 55 is dropped into the bore of the drill string and passes downwardly. The nose of the "go-devil" 26 as shown in Fig. 7, enters between the trigger fingers and swings the latter so as to release them from the seating ledge 23. The "go-devil" next strikes the shoulder 25 and forces the connector sleeve 60

to its lower position. In its movement downwardly, it engages the upper head 37 and forces the mandrel down to collapsed position as shown in Fig. 7. Circulation may now be continued by way of the ports 32 which have been uncovered. The bit in collapsed position may then be pulled and on insertion in the well hole again, the parts are placed in the position shown in Fig. 1.

What I claim is:—

1. An expandible bit comprising a slotted body, cutter carriers fulcrumed in said slots transverse of the drilling axis of said bit so that their cutter ends may be swung outwardly to expanded position and inwardly to collapsed position, an axially movable mandrel having upper and lower heads, a cavity formed between said carriers below their fulcrums to accommodate the lower head, said heads being spaced in relation to said carriers so that with progressive advance of the mandrel towards the lower end of the body the lower head is disposed in said cavity to enable collapsion of the carriers, then the lower head is disposed between said carriers to expand said carriers, and next the lower head is cleared of said carriers and the upper head is disposed between said carriers to collapse the latter, and means to advance said mandrel.

2. An expandible bit comprising a slotted body, cutter carriers fulcrumed in said slots transverse of the drilling axis of said bit so that their cutter ends may be swung outwardly to expanded position and inwardly to collapsed position, an axially movable mandrel having upper and lower heads, spaced cavities formed between and by said carriers below the fulcrums of said carriers to accommodate the lower head, said heads being so spaced with relation to said carriers that with progressive advance of the mandrel toward the lower end of the body the lower head is disposed in the upper cavity to enable collapsion of the carriers with the upper head clear of said carriers, then the lower head is disposed in a cavity between said carriers to expand said carriers and with the upper head clear of said carriers, and next the lower head is disposed in the lower cavity and the upper head between said carriers to collapse the latter, and means to advance said mandrel.

3. An expandible bit comprising a slotted body, cutter carriers fulcrumed in said slots transverse of the drilling axis of said bit so that their cutter ends may be swung outwardly to expanded position and inwardly to collapsed position, an axially movable mandrel having upper and lower heads, spaced cavities formed between and by said carriers, one each to accommodate a head, said cavities being spaced with relation to said heads so that with progressive advance of the mandrel toward the lower end of the body the lower

head is disposed in a cavity to enable collapse of the carriers with said upper head clear of said carriers, then the lower head is disposed out of said cavity between said carriers and below their fulcrums and the upper head is disposed in a cavity to expand said carriers, and next the lower head is disposed in a cavity and the upper head out of a cavity and between said carriers and above 10 their fulcrums to collapse the latter, and means to advance said mandrel.

4. An expandible bit comprising a slotted body, cutter carriers fulcrumed in said slots transverse of the drilling axis of said bit so 15 that their cutter ends may be swung outwardly to expanded position and inwardly to collapsed position, and axially movable mandrel having upper and lower heads, three spaced cavities formed between and by said 20 carriers to accommodate said heads, the two lower cavities being contiguous, said cavities being spaced so that with progressive advance of the mandrel toward the lower end of the body the lower head is disposed in the 25 intermediate cavity to enable collapse of the carriers and the upper head clear of said carriers, then the lower head is disposed out of the intermediate cavity and between said carriers with said upper head in the upper 30 cavity to expand said carriers, and next the lower head is disposed in the lower cavity and the upper head out of the upper cavity and between said carriers to collapse the latter, and means to advance said mandrel.

35 5. An expandible bit comprising a slotted body, cutter carriers pivoted intermediate of their ends in said slots transverse of the drilling axis of said bit so that their cutter ends may be swung outwardly to expanded position and inwardly to collapsed position, an axially movable mandrel having upper and lower heads with their lower ends tapered, three spaced cavities formed between and by said carriers to accommodate said heads, 40 said cavities being spaced with relation to said carriers so that with progressive advance of the mandrel toward the lower end of the body the lower head is disposed in the intermediate cavity and the upper head clear 45 of said carriers to enable collapse of the carriers, then the lower head is disposed out of said intermediate cavity between said carriers and the upper head in the upper cavity to expand said carriers, and next the lower 50 head is disposed in the lower cavity and the upper head between said carriers to collapse the latter, and means to advance said mandrel.

55 6. An expandible bit comprising a slotted body and a bore, cutter carriers fulcrumed in said slots transverse of the drilling axis of said bit so that their cutter ends may be swung outwardly to expanded position and inwardly to collapsed position, an axially movable mandrel having upper and lower heads and 60 a passage extending therethrough communi-

cating with said bore, a check valve controlling said passage to prevent outflow of liquid, a cavity formed between said carriers below their fulcrums to accommodate the lower head, said heads being spaced in relation to said carriers so that with progressive advance of the mandrel toward the lower end of the body the lower head is disposed in said cavity to enable collapse of the carriers, then the lower head is disposed between said carriers to expand said carriers, and next the lower head is cleared of said carriers and the upper head is disposed between said carriers to collapse the latter, and means to advance said mandrel.

7. An expandible bit comprising a slotted body and a bore, cutter carriers fulcrumed in said slots transverse of the drilling axis of said bit so that their cutter ends may be swung outwardly to expanded position and inwardly to collapsed position, an axially movable mandrel having upper and lower heads and a passage extending therethrough communicating with said bore, a check valve controlling said passage to prevent outflow of liquid, spaced cavities formed between and by said carriers below the fulcrums of said carriers to accommodate the lower head, said heads being spaced so with relation to said carriers that with progressive advance of the mandrel toward the lower end of the body the lower head is disposed in the upper cavity to enable collapse of the carriers with the upper head clear of said carriers, then the lower head is disposed between said carriers to expand said carriers and with the upper head clear of said carriers, and next the lower head is disposed in the lower cavity and the upper head between said carriers to collapse the latter, and means to advance said mandrel.

8. An expandible bit comprising a slotted body and a bore, cutter carriers fulcrumed in said slots transverse of the drilling axis of said bit so that their cutter ends may be swung outwardly to expanded position and inwardly to collapsed position, an axially movable mandrel having upper and lower heads and a passage extending therethrough communicating with said bore, a check valve controlling said passage to prevent outflow of liquid, spaced cavities formed between and by said carriers, one each to accommodate a head, said cavities being spaced with relation to said heads so that with progressive advance of the mandrel toward the lower end of the body the lower head is disposed in a cavity to enable collapse of the carriers with said upper head clear of said carriers, then the lower head is disposed out of said cavity between said carriers and below their fulcrums and the upper head is disposed in a cavity to expand said carriers, and next the lower head is disposed in a cavity and the upper head out of a cavity and between said

carriers and above their fulcrums to collapse the latter, and means to advance said mandrel.

9. An expandible bit comprising a slotted body and bore, cutter carriers fulcrumed in said slots transverse of the drilling axis of said bit so that their cutter ends may be swung outwardly to expanded position and inwardly to collapsed position, an axially movable mandrel having upper and lower heads and a passage extending therethrough communicating with said bore, a check valve controlling said passage to prevent outflow of liquid, three spaced cavities formed between and by said carriers to accommodate said heads, the two lower cavities being contiguous, said cavities being spaced so that with progressive advance of the mandrel toward the lower end of the body the lower head is disposed in the intermediate cavity to enable collapse of the carriers and the upper head clear of said carriers, then the lower head is disposed out of the intermediate cavity and between said carriers with said upper head in the upper cavity to expand said carriers, and next the lower head is disposed in the lower cavity and the upper head out of the upper cavity and between said carriers to collapse the latter, and means to advance said mandrel.

10. An expandible bit comprising a slotted body and a bore, cutter carriers pivoted intermediate of their ends in said slots transverse of the drilling axis of said bit so that their cutter ends may be swung outwardly to expanded position and inwardly to collapsed position, an axially movable mandrel having upper and lower heads with their lower ends tapered, said mandrel having a passage extending therethrough communicating with said bore, a check valve controlling said passage to prevent outflow of liquid, three spaced cavities formed between and by said carriers to accommodate said heads, said cavities being spaced with relation to said carriers so that with progressive advance of the mandrel toward the lower end of the body the lower head is disposed in the intermediate cavity and the upper head clear of said carriers to enable collapse of the carriers, then the lower head is disposed out of said intermediate cavity between said carriers and the upper head in the upper cavity to expand said carriers, and next the lower head is disposed in the lower cavity and the upper head between said carriers to collapse the latter, and means to advance said mandrel.

11. An expandible bit comprising a slotted body, cutter carriers fulcrumed in said slots transverse of the drilling axis of said bit so that their cutter end may be swung outwardly to expanded position and inwardly to collapsed position, an axially movable mandrel having upper and lower heads, a cavity

formed between said carriers below their fulcrums to accommodate the lower head, said heads being spaced in relation to said carriers so that with progressive advance of the mandrel toward the lower end of the body the lower head is disposed in said cavity to enable collapse of the carriers, then the lower head is disposed between said carriers to expand said carriers, and next the lower head is cleared of said carriers and the upper head is disposed between said carriers to collapse the latter, and means to control advance of said mandrel comprising a telescopic connector mounted on the upper end of said mandrel and axially slidible in said body, releasable means to hold said connector in said body against downward movement and permit limited downward movement of said mandrel to expansion position, and means to disengage said releasable means and permit said connector to follow said mandrel to collapse position.

12. An expandible bit comprising a slotted body, cutter carriers fulcrumed in said slots transverse of the drilling axis of said bit so that their cutter ends may be swung outwardly to expanded position and inwardly to collapsed position, an axially movable mandrel having upper and lower heads, spaced cavities formed between and by said carriers below the fulcrums of said carriers to accommodate the lower head, said heads being spaced so with relation to said carriers that with progressive advance of the mandrel toward the lower end of the body the lower head is disposed in the upper cavity to enable collapse of the carriers with the upper head clear of said carriers, then the lower head is disposed between said carriers to expand said carriers and with the upper head clear of said carriers and next the lower head is disposed in the lower cavity and the upper head between said carriers to collapse the latter, and means to control advance of said mandrel comprising a telescopic connector mounted on the upper end of said mandrel and axially slidible in said body, releasable means to hold said connector in said body against downward movement and permit limited downward movement of said mandrel to expansion position, and means to disengage said releasable means and permit said connector to follow said mandrel to collapse position.

13. An expandible bit comprising a slotted body, cutter carriers fulcrumed in said slots transverse of the drilling axis of said bit so that their cutter ends may be swung outwardly to expanded position and inwardly to collapsed position, an axially movable mandrel having upper and lower heads, spaced cavities formed between and by said carriers, one each to accommodate a head, said cavities being spaced with relation to said heads so that with progressive advance

of the mandrel toward the lower end of the body the lower head is disposed in a cavity to enable collapsing of the carriers with the upper head clear of said carriers, then the 5 lower head is disposed out of said cavity between said carriers and below their fulcrums and the upper head is disposed in a cavity to expand said carriers, and next the lower head is disposed in a cavity and the 10 upper head out of a cavity and between said carriers and above their fulcrums to collapse the latter, and means to advance said mandrel, means to control advance of said mandrel comprising a telescoping connector 15 mounted on the upper end of said mandrel and axially slidably in said body, releasable means to hold said connector in said body against downward movement and permit limited downward movement of said mandrel 20 to expansion position, and means to disengage said releasable means and permit said connector to follow said mandrel to collapse position.

14. An expandible bit comprising a slotted body, cutter carriers fulcrumed in said slots transverse of the drilling axis of said bit so that their cutter ends may be swung outwardly to expanded position and inwardly to collapsed position, an axially movable 25 mandrel having upper and lower heads, three spaced cavities formed between and by said carriers to accommodate said heads, the two lower cavities being contiguous, said cavities being spaced so that with progressive 30 advance of the mandrel toward the lower end of the body the lower head is disposed in the intermediate cavity to enable collapsing of the carriers and the upper head clear of said carriers, then the lower head 35 is disposed out of the intermediate cavity and between said carriers with said upper head in the upper cavity to expand said carriers, and next the lower head is disposed in the lower cavity and the upper head out of the 40 upper cavity and between said carriers to collapse the latter, and means to control advance of said mandrel comprising a telescopic connector mounted on the upper end of said mandrel and axially slidably in said 45 body, releasable means to hold said connector in said body against downward movement and permit limited downward movement of said mandrel to expansion position, and means to disengage said releasable means 50 and permit said connector to follow said mandrel to collapsible position.

15. An expandible bit comprising a slotted body, cutter carriers pivoted intermediate of their ends in said slots transverse of the 55 drilling axis of said bit so that their cutter ends may be swung outwardly to expanded position and inwardly to collapsed position, an axially movable mandrel having upper and lower heads with their lower ends tapered, three spaced cavities formed between 60

and by said carriers to accommodate said heads, said cavities being spaced with relation to said carriers so that with progressive advance of the mandrel toward the lower end of the body the lower head is disposed in the intermediate cavity and the upper head clear of said carriers to enable collapsing of the carriers, then the lower head is disposed out of said intermediate cavity between said carriers and the upper head in 70 the upper cavity to expand said carriers, and next the lower head is disposed in the lower cavity and the upper head between said carriers to collapse the latter, and means to control advance of said mandrel comprising a telescopic connector mounted on the upper end of said mandrel, and axially slidably in said body, releasable means to hold said connector in said body against downward movement and permit limited downward movement of said mandrel to expansion position, and means to disengage said releasable means and permit said connector to follow said mandrel to collapse position.

16. An expandible bit comprising a slotted body and a bore for connection to drill pipe, cutter carriers fulcrumed in said slots transverse of the drilling axis of said bit so that their cutter ends may be swung outwardly to expanded position and inwardly to collapsed position, an axially movable mandrel having upper and lower heads and a passage 90 extending therethrough communicating with said bore, a check valve controlling said passage to prevent outflow of liquid, a cavity 95 formed between said carriers below their fulcrums to accommodate the lower head, said heads being spaced in relation to said carriers so that with progressive advance of the mandrel toward the lower end of the body the lower head is disposed in said cavity to enable collapsing of the carriers, then the lower head is disposed between said carriers to expand said carriers, and the lower head is cleared of said carriers and the upper 100 head is disposed between said carriers to collapse the latter, and means to control advance of said mandrel comprising a telescopic connector mounted on the upper end of said mandrel and axially slidably in said body, trip means to hold said connector in said body against downward movement and having trigger fingers projecting into the bore of said connector, said connector permitting downward movement of said mandrel to expansion position, and a plummet 105 for passage through the circulation bore of the drill string and into the bore of said connector to engage said fingers and release said connector to permit the latter to follow 110 said mandrel to collapse position.

17. An expandible bit comprising a slotted body and a bore for connection to a drill pipe, cutter carriers fulcrumed in said slots transverse of the drilling axis of said bit 115

so that their cutter ends may be swung outwardly to expanded position and inwardly to collapsed position, an axially movable mandrel having upper and lower heads and a passage extending therethrough communicating with said bore, a check valve controlling said passage to prevent outflow of liquid, spaced cavities formed between and by said carriers below the fulcrums of said carriers to accommodate the lower head, said heads being spaced so with relation to said carriers that with progressive advance of the mandrel toward the lower end of the body the lower head is disposed in the upper cavity to enable collapson of the carriers with the upper head clear of said carriers, then the lower head is disposed between said carriers to expand said carriers and with the upper head clear of said carriers, to expand said carriers and with the upper head clear of said carriers, and next the lower head is disposed in the lower cavity and the upper head between said carriers to collapse the latter, and means to control advance of said mandrel comprising a telescopic connector mounted on the upper end of said mandrel and axially slidale in said body, trip means to hold said connector in said body against downward movement and having trigger fingers projecting into the bore of said connector, said connector permitting downward movement of said mandrel to expansion position, and a plummet for passage through the circulation bore of the drill string and into the bore of said connector to engage said fingers and release said connector to permit the latter to follow said mandrel to collapson position.

18. An expansible bit comprising a slotted body and a bore for connection to a drill pipe, cutter carriers fulcrumed in said slots transverse of the drilling axis of said bit so that their cutter ends may be swung outwardly to expanded position and inwardly to collapsed position, an axially movable mandrel having upper and lower heads and a passage extending therethrough communicating with said bore, a check valve controlling said passage to prevent outflow of liquid, spaced cavities formed between and by said carriers, one each to accommodate a head, said cavities being spaced with relation to said heads so that with progressive advance of the mandrel toward the lower end of the body the lower head is disposed in a cavity to enable collapson of the carriers with said upper head clear of said carriers, then the lower head is disposed out of said cavity between said carriers and below their fulcrums and the upper head is disposed in a cavity to expand said carriers, and next the lower head is disposed in a cavity and the upper head out of a cavity and between said carriers and above their fulcrums to collapse the latte , and means to control advance of said mandrel comprising a tele-

scopic connector mounted on the upper end of said mandrel and axially slidale in said body, trip means to hold said connector in said body against downward movement and having trigger fingers projecting into the bore of said connector, said connector permitting downward movement of said mandrel to expansion position, and a plummet for passage through the circulation bore of the drill string and into the bore of said connector to engage said fingers and release said connector to permit the latter to follow said mandrel to collapson position. 70

19. An expansible bit comprising a slotted body and bore for connection to a drill pipe, cutter carriers fulcrumed in said slots transverse of the drilling axis of said bit so that their cutter ends may be swung outwardly to expanded position and inwardly to collapsed position, an axially movable mandrel having upper and lower heads and a passage extending therethrough communicating with said bore, a check valve controlling said passage to prevent outflow of liquid, three spaced cavities formed between and by said carriers to accommodate said heads, the two lower cavities being contiguous, said cavities being spaced so that with progressive advance of the mandrel toward the lower end of the body the lower head is disposed in the intermediate cavity to enable collapson of the carriers and the upper head clear of said carriers, then the lower head is disposed out of the intermediate cavity and between said carriers with said upper head in the upper cavity to expand said carriers, and next the lower head is disposed in the lower cavity and the upper head out of the upper cavity and between said carriers to collapse the latter, and means to control advance of said mandrel comprising a telescopic connector mounted on the upper end of said mandrel and axially slidale in said body, trip means to hold said connector in said body against downward movement and having trigger fingers projecting into the bore of said connector, said connector permitting downward movement of said mandrel to expansion position, and a plummet for passage through the circulation bore of the drill string and into the bore of said connector to engage said fingers and release said connector to permit the latter to follow said mandrel to collapson position. 95

20. An expansible bit comprising a slotted body and a bore for connection to a drill pipe, cutter carriers pivoted intermediate of their ends in said slots transverse of the drilling axis of said bit so that their cutter ends may be swung outwardly to expanded position and inwardly to collapsed position, an axially movable mandrel having upper and lower heads with their lower ends tapered, said mandrel having a passage extending therethrough communicating with said bore, a check valve controlling said passage to pre- 125

vent outflow of liquid, three spaced cavities formed between and by said carriers to accommodate said heads, said cavities being spaced with relation to said carriers so that
5 with progressive advance of the mandrel toward the lower end of the body the lower head is disposed in the intermediate cavity and the upper head clear of said carriers to enable collapse of the carriers, then
10 the lower head is disposed out of said intermediate cavity between said carriers and the upper head in the upper cavity to expand said carriers, and next the lower head is disposed in the lower cavity and
15 the upper head between said carriers to collapse the latter, and means to control advance of said mandrel comprising a telescopic connector mounted on the upper end of said mandrel and axially slidable in said body, trip means to hold said connector in said body against downward movement and having trigger fingers projecting into the bore of said connector, said connector permitting
20 downward movement of said mandrel to expansion position, and a plummet for passage through the circulation bore of the drill string and into the bore of said connector to engage
25 said fingers and release said connector to permit the latter to follow said mandrel to collapse position.
30

In witness that I claim the foregoing I have hereunto subscribed my name this 12th day of April, 1930.
